UNITED STATES PATENT OFFICE.

JOHN T. WHITEHOUSE, OF CLEVELAND, OHIO, ASSIGNOR TO THE VAN DORN IRON WORKS COMPANY, OF CLEVELAND, OHIO, A CORPORATION OF OHIO.

JAIL-DOOR-LOCKING MECHANISM.

Application filed August 11, 1924. Serial No. 731,384.

This invention relates to improvements in jail door locking mechanism and is a continuation of my prior Patent No. 1,543,140, granted June 23, 1925.

5 The objects of this invention are to provide a simplified means for locking the several doors of the jail cells and to provide also simplified means for controlling the locking mechanism of the doors; to provide 10 also simplified means for indicating the open or closed condition of the several individual doors and to provide means for preventing jamming of the lock bolt by shutting of the door thereagainst; and also 15 to provide means for preventing the indication of closed condition of any given door unless and until the particular door is actually and effectively closed and locked.

A further object of the present invention 20 is to provide an improved means for mounting part of the lock controlling mechanism so that the position of such mechanism can be varied in connection with the different doors according to the number of doors 25 which are included and in this way facilitate the arrangement of the control mechanism with an accompanying economizing of space.

It is to be understood that the lock 30 control mechanism as here disclosed is capable of application and adaptation to any number of doors in the same manner as in the companion case above referred to; and, except as specifically pointed out in the present case, the structure and arrangement of parts 35 are the same in this case as in the said previous application.

Other objects will appear from the following description and claims when considered together with the accompanying drawings.

Fig. 1 shows in elevation the control means for the door locking mechanism; Fig. 2 is an enlarged detail view of part of the same mechanism as shown in Fig. 1; Fig. 3 shows in elevation the arrangement of control levers and chain connections leading to the track box above the cell doors; Fig. 4 is taken on line 4—4, Fig. 1; Fig. 5 is a detail view taken on line 5—5, Fig. 1; Fig. 6 shows the subject matter of Fig. 5 at 90°; Fig. 7 is taken on line 7—7 of Fig. 1; Fig. 8 is taken on line 8—8 of Fig. 2, and Figs. 9 and 10 are detail views of the bell crank lever which forms part of the control 55 mechanism for the lock.

As more fully explained in the companion application above referred to, each cell is provided with a sliding door 1, which opens to the prisoner's corridor separated by a 60 partition wall or grating from the warden's room or corridor. The warden has access from his compartment or corridor to the control box 2 within which are enclosed the levers for controlling the locking mechanism of the several doors. Only two doors are indicated in the present case and each door is suspended from a hanger 3 mounted upon rollers which engage tracks for rolling movement along the track box. The track 70 box extends above the cells and encloses part of the lock controlling mechanism. At the closing edge of the door in each case there is provided the pilaster 4 which encloses the latch itself and into which the latch bar 6 carried by the door is adapted to project for locking engagement by the latch. A suitable cover is provided for each pilaster and a cover means is provided also for the track box in the same manner as in the companion application above referred to. As also more fully explained in said co-pending application, the door between the warden's chamber and the prisoner's corridor is locked by means of bolt 7 which in turn is controlled by the hand lever 8. Corresponding to each door there is provided a control lever 9, which levers are arranged in two tiers, as clearly indicated in Figs. 1 and 3, and which occupy raised position when the doors are locked and lower or horizontal position when they are unlocked, as clearly shown in Fig. 3. Another control lever 10 is provided for controlling the locking means 10a for the covers of the track box in the same manner as disclosed in the companion application, and the lever bar 11 serves to control the mechanism for moving the doors toward closing position, as more fully explained in the said companion application and as will be more fully referred to later in the present application.

The latch 5, as more clearly indicated in Figs. 5 and 6, is normally forced down-

wardly by the spring 12 which engages at one end the pin 13 fixed to the latch bolt, the latch being guided in such vertical movement by means of guideways 14 secured within the pilaster. The other end of the spring 12 is anchored by nut 15^a threaded on bolt 15 which in turn extends up through the lower end portion of the guideway 14. In this way the tension of the spring and hence the position of the bolt may be adjusted, if necessary, by turning nut 15^a. The pin 16^a is a stop to limit the downward movement of the latch rod 16. The latch as it projects through the lower end of the guideway 14 is adapted to engage in the notch provided in the latch bar 6 carried by the door as it projects through an opening permitting its entrance into the pilaster. The latch 5 is mounted upon the lower end of the vertical rod 16 which extends up through the pilaster and projects through the top thereof into the lower portion of the track box, the upper end of the same being provided with a pivotal connection at 17^a with one arm portion of a bell crank lever 17 which in turn is pivotally mounted upon the fixed bracket 18. The main arm of the bell crank lever 17 is connected at the point 19 with a chain 20 which extends out through the end of the track box into the upper compartment of the casing and over the proper guide bracket, as illustrated in Fig. 3, this means being the same as that provided in the companion application between the control lever and the lock controlling mechanism in the track box. From this it will be seen that upon lowering the proper lever for a particular door, the latch will be raised against the tension of the spring 12 so as to unlock the door and permit the same to open.

At the same time another locking means which is provided for securing the door in closed position is unlocked or released by the same lowering movement of the lever in the control box. This second lock comprises a latch bolt 21 which is adapted for vertical movement through the arms of a bracket 22 carried by the hanger member 3 of the door and which is adapted to engage at its lower end the recess 23 provided in the upper side of gap nut 24. As before explained, the hanger member upon which the door is suspended is adapted to move along on the track box by means of rollers which are provided with a suitable track for this purpose. When the gap nut 24 occupies the position shown in Fig. 1, the latch bolt 21 is adapted to engage the recess 23 therein so as to maintain the door in closed position, the control lever 11 being at this time in the lower position as indicated in Fig. 1. This mechanism is of the same structure and has the same manner of operation as in the aforesaid companion application except for

the particular means by which the latch bar 21 is lifted out of engagement with the recess 23. In the present case the latch bolt 21 is raised by engagement of the bar 26 which is pivotally connected at the point 27 with the intermediate link 28 which in turn is pivotally mounted at 29 on the depending arm 30 mounted in the top of the track box. The bar 26 is adapted to be moved toward the left, as viewed in Fig. 1, by means of the rod or wire 31 to which it is connected and which is pivotally connected at 32 to the upper end of the bell crank lever 33. The bell crank lever 33 is pivotally mounted on the upper part of stationary bracket 18 and has pivotal connection at the point 34 with the upper end of a connecting rod or link 35 which is in turn pivotally connected at its other end at the point 36 to the main bell crank lever 17. By means of these connections it will be seen that upon operation of the chain 20 by depressing the corresponding lever in the control box, the latch 5 will not only be raised out of locking engagement with the door latch bar 6, but the bar 26 will also be moved toward the left and will be raised vertically sufficiently to engage the roller 37 on the upper end of the latch bolt 21 so as to raise the latch bolt out of engagement with the notch 23 in the gap nut. The door is then released completely so as to be free for opening movement.

Simultaneously with the two unlocking operations just described, another operation takes place upon the lowering of the control lever for any door. This other operation involves several parts which are mounted in the tripper case 38 which is secured in the left hand upper part of the track box, such a tripper case being provided for each door. The mechanism now to be referred to is shown in detail in Fig. 8 and comprises the detent 39 which is pivotally mounted at the point 40 for movement in a lateral plane, this detent being under the influence of spring 41 on the one side. A spring 42 surrounds the rod 43 which might be considered the plunger rod of plunger 44 enclosed in the tripper case, the other end of the spring 42 having suitable bearing. When the door is in closed position, the tripper pin 44^a carried thereby is adapted to engage the plunger 44 so as to compress the spring 42 and force the rod 43 toward the left, as indicated in dotted lines in Fig. 8, and move the detent 39 toward the left against the tension of the spring 41. With the detent 39 occupying such position, that is when the door is closed, the upwardly extending rod or pin 45 which is pivotally connected at the point 45^a at its lower end to the one arm of the main bell crank lever, is adapted to project upwardly past the detent 39 so as to permit the control lever to

return to its upper position for indicating locked condition of the door. When, however, the door is open, the detent is moved toward the right, as viewed in Fig. 8, by 5 the spring 41 so as to occupy position directly above the pin or rod 45 and thus prevent vertical movement of the pin 45, or in other words will prevent movement of the control lever to its fully raised position. In this

10 way, so long as the door is in open position or in other words until the door is in fully closed and actually locked position, the control lever will remain in lowered position corresponding to the position indicated by 15 the word "unlocked" in Fig. 3, and will accordingly indicate such condition of the door. Likewise while the door is open, the interlocking mechanism just now described will maintain the latch 5 in raised position 20 while the door is in open position and in this way will prevent jamming of the latch 5 as might otherwise be caused by the prisoner slamming the door. Upon releasing the two-fold locking mechanism of the door so 25 as to permit the same to open, the tension of the spring 42 upon the door being released will through its engagement with the tripper pin 44^a spring the door to slightly open position.

30 Another particular feature of the present invention relates to the special form of bracket 18 which is here shown as being secured at its one end in the upper part of the pilaster while its other end is secured 35 to the lower side of the tripper case. This bracket is of angular form, as clearly indicated in Fig. 7, and extends in spaced relation to the rear of the track box so as to afford suitable accommodation for the bell 40 crank lever mechanism which is mounted thereupon. This bracket is provided with a series of openings so that the bell crank lever 17 can be mounted at the proper elevation thereon according to the number of 45 the cell to which it corresponds. The plate 18^a is removably secured in position on bracket 18 by means of bolts and carries the countersunk bolt 18^b upon which the lever 17 is mounted. Thus this removable structure 50 can be applied as a unit to bracket 18 at any elevation desired, while the bracket 18 is part of the permanent frame structure. As clearly set forth in the companion application, the chains 20 which lead from the 55 control box to the control levers for the several doors, are arranged in a vertical bank one above the other. So that in the present case the bell crank lever corresponding to cell 1 will occupy lowermost position, bell crank lever for door 2 will be mounted upon bracket 18 in the next higher position and so on, the series of openings in each bracket permitting the same bracket 60 to be used throughout and to be mounted in the same manner and in the same cor-

responding position. The rods 16, 35 and 45 must of course be of proper length for each door.

Sufficiently large openings are provided in the top of the pilaster so as to permit 70 the bell crank lever 17 to be mounted on the lower part of the bracket and extend with its connections up through the pilaster to the track box.

Briefly the operation is as follows: Assuming the doors to all be in locked condition, as illustrated in Fig. 1, and assuming that it is desired to open a given door; the proper lever, as indicated by a corresponding number in the control box, will 80 be depressed to fully lowered position so as to release the latch 5 and at the same time release also the latch bolt 21. The door is then free to open and will be sprung open to a certain extent by the spring 42. At the same time the pin 45 upon being lowered permits the detent 39 to move to 85 the right, as viewed in Fig. 8, so as to intercept and thus prevent upward movement of the pin 45 so long as the door remains 90 in open position. In this way the control lever is prevented from returning to upper or "unlocked" position until the detent 39 is moved to the left by actually and effectively closing and locking the door. Re-

lease of the control lever, upon opening the door, will permit such lever to move to substantially horizontal position, as indicated by dotted lines in Fig. 2, corresponding to unlocked position as indicated in Fig. 3. 100 The door may then be more fully opened by the warden or by the prisoner himself. Then, when it is desired to close and lock the door, this may be accomplished by the prisoner or the warden actually moving the 105 door itself to fully closed position so that the latch bolt 6 projects into the pilaster. At the same time the tripper pin 44^a is brought into engagement with the plunger 44 and forces the detent 39 to the left so as 110 to permit upward movement of the pin 45 by the action of the spring 12. At the same time spring 12 forces latch 5 to locking engagement with the latch bolt 6. This closing operation of the door at the same 115 time also moves the hanger, upon which the door is suspended, along the track box so as to cause the latch bolt 21 to ride up the inclined face of gap nut and to drop into the notch 23 for locking engagement therewith. Should, however, the 120 warden desire to close the door of a given cell without going into the prisoner's corridor, this may be done by raising the control lever 11 to fully raised position and then lowering same. Such operation is effected through the rack and gear mechanism 46, more fully described in the companion application and in the same manner as there set forth. Briefly, the gap nut of each 125

130

door is moved first to the right to the full extent of opening of the several doors so as to permit the latch bolts 21 of the several doors to ride up the inclined faces of the 5 gap nuts and to be engaged by the shoulders or high walls of the recesses 23; then upon lowering lever 11, the doors are moved to closed position. It will be observed that upon lowering lever 11, the latch bolt 21 10 is not permitted to be lowered to the bottom of the recess 23 but occupies such position that its lower end is just free of the one side of the notch 23. This is for the purpose of permitting the gap nuts to be 15 moved to the right at any time by operation of the lever 11 so as to close any door which might have been left open without disturbing or being interfered with by the depending latch bolts of any other doors 20 which might already be effectively closed and locked. This feature is more fully explained in the companion application above referred to.

What I claim is:

- 25 1. A jail door locking mechanism comprising a lock bolt adapted for straight line movement into and out of locking position, means for holding said lock bolt in unlocked position, and means carried by the door for releasing said holding means and permitting locking engagement therewith.
- 30 2. A jail door locking mechanism comprising a spring-actuated lock bolt adapted for straight line movement into and out of locking position, means for holding said lock bolt in unlocked position, and means carried by the door for releasing and holding means and permitting locking engagement therewith.
- 35 3. A jail door locking mechanism comprising a lock bolt adapted for straight line movement into and out of locking position, means for holding said lock bolt in unlocked position, and means adapted for actuation by closing of the door for releasing said holding means and permitting locking engagement therewith.
- 40 4. In a jail door locking mechanism, the combination of a door, separate means including a lock bolt having straight line movement for locking said door closed, and operative connections between said locking means whereby one of them can be further actuated without affecting the other.
- 45 5. In a jail door mechanism, the combination of a door, means for locking said door including a lock bolt having straight-line movement into and out of locking position, means for operating said locking means and
- 50 indicating open or closed condition of the door, said means being so constructed and arranged that the open position of the door will be so indicated until the door is closed and actually locked.
- 55 6. In a jail door mechanism, the combina-

tion of a door, means for locking said door, and spring actuated means arranged entirely above said door for preventing throwing of said locking means except when the door is closed.

7. In a jail door mechanism, the combination of a door, means for locking said door, means for indicating open or closed condition of the door, and means arranged entirely above said door so that open position of the door will be indicated until the door is closed and actually locked.

8. In a jail door mechanism, the combination of a door, means for locking said door, means for indicating open or closed condition of the door, and means located away from the region of the door whereby open position of the door will be indicated until the door is closed and actually locked.

9. In a jail door mechanism, the combination of a door, means for locking said door, a casing arranged above said door, and spring actuated means arranged entirely within said casing for preventing throwing of said locking means except when the door is closed.

10. In a jail door mechanism, the combination of a door, means for locking said door, spring actuated means for preventing throwing of said locking means except when the door is closed, a single lever control means connecting said locking means and preventing means, and means for operating said lever control means.

11. In a jail door locking mechanism, the combination of a door, separate means including a lock bolt having straight line movement for locking said door in closed position, a single lever control means operatively connecting said separate locking means, and means for operating said lever control means.

12. In a jail door locking mechanism, the combination of a door, separate means having a lock bolt having straight line movement for locking said door in closed position, a bell crank lever operatively connecting said separate locking means, and means for operating said lever.

13. In a jail door locking mechanism, the combination of a door, separate means for locking said door in closed position, spring actuated means for preventing throwing of said locking means except when the door is closed, a single lever control means operatively connecting said locking means and preventing means, and means for operating said lever control means.

14. In a jail door mechanism, the combination of a plurality of doors, a track box extending above said doors, means for controlling said doors, said control means being located in said track box at different elevations according to the respective doors, and a bracket provided for supporting part

- of said controlling means for each door, said brackets being mounted at the same level throughout and each being adapted for mounting of the controlling means for any door.
15. In a jail door mechanism, the combination of a plurality of doors, a track box extending above said doors, means for controlling said doors, said control means being located in said track box at different elevations according to the respective doors, and a vertically extending bracket provided for supporting part of the door-controlling means for each door, said brackets being provided with vertically spaced apertures 15 and being mounted at the same level throughout, thereby serving to support the controlling means for any door.
- In testimony whereof I hereby affix my signature.

JOHN T. WHITEHOUSE.
